US00D843390S

(12) **United States Design Patent** (10) **Patent No.:** **US D843,390 S**
Protzman et al. (45) **Date of Patent:** **** Mar. 19, 2019**

(54) **DISPLAY SCREEN OR PORTION THEREOF
WITH GRAPHICAL USER INTERFACE**

(71) Applicant: **Lutron Electronics Co., Inc.**,
Coopersburg, PA (US)

(72) Inventors: **Brent Protzman**, Easton, PA (US);
Michelle L. Greene, Bethlehem, PA (US); **Erica L. Clymer**, Northampton, PA (US); **Jennifer Wong**, Breinigsville, PA (US); **Laura Marie Friedlander**, Harleysville, PA (US); **Joseph Roy Parks**, Emmaus, PA (US); **Edward J. Blair**, Telford, PA (US)

(73) Assignee: **Lutron Electronics Co., Inc.**,
Coopersburg, PA (US)

(**) Term: **15 Years**

(21) Appl. No.: **29/642,970**

(22) Filed: **Apr. 3, 2018**

Related U.S. Application Data

(63) Continuation of application No. 29/583,433, filed on Nov. 4, 2016, now Pat. No. Des. 815,653, which is a continuation of application No. 29/525,147, filed on Apr. 27, 2015, now Pat. No. Des. 771,072.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 shows a display screen or portion thereof with graphical user interface showing our new design; FIG. 2 shows a second embodiment thereof; and, FIG. 3 shows a third embodiment thereof.

(Continued)

The dashed broken lines illustrate a display screen or portion thereof, and form no part of the claimed design.
